UNITED STATES PATENT OFFICE

166,134

CHENILLE TEXTILE FABRIC

Larry Silberberg, New York, N. Y.

Application December 14, 1951, Serial No. 17,730

Term of patent 7 years

(Cl. D92—1)

To all whom it may concern:

Be it known that I, Larry Silberberg, a citizen of the United States of America, residing in New York, county of New York, and State of New York, have invented a new, original, and ornamental Design for a Chenille Textile Fabric, of which the following is a specification, reference being had to the accompanying drawing, forming part thereof.

Fig. 1 is a plan view of a chenille textile fabric, showing my new design.

Fig. 2 is an edge view thereof. A design unit is outlined by broken lines and is repeated as indicated.

I claim:

The ornamental design for a chenille textile fabric, substantially as shown and described.

LARRY SILBERBERG.
